UNITED STATES PATENT OFFICE.

AUGUST F. LUZZI, OF HOUSTON, TEXAS, ASSIGNOR TO J. B. AKERS, OF BRECKENRIDGE, TEXAS.

TRUSS.

Application filed September 28, 1926. Serial No. 138,174.

This invention relates to new and useful improvements in a truss.

One object of the invention is to provide a truss of the character described, specially designed for use in retaining the injured or protruding parts in proper position in case of hernia, or rupture.

Another object of the invention is to provide a truss, or rupture support which is so designed that it will retain the protruding hernia in place and will impart a massaging effect to the surrounding muscles and thus stimulate increased circulation throughout the weakened muscular area with the result that the weakened muscles will become gradually strengthened and will close the aperture through which the hernia protrudes.

A further feature of the invention resides in the provision of a truss of the character described having an adjustable retaining pad formed to retain the hernia in place and which is so mounted in the truss as to readily yield so as not to be uncomfortable or cause an enlargement of the hernia opening through the abdominal wall.

A still further feature of the invention resides in improved means for retaining the truss in place on the body of the patient.

With the above and other objects in view the invention has particular relation to certain novel features of construction, operation and arrangement of parts, an example of which is given in this specification and illustrated in the accompanying drawings, wherein:—

Figure 1 shows a front elevation of the truss, as applied to the body of a wearer and designed for use on a single rupture.

Figure 2 shows a front elevation thereof, as applied to the body of a wearer, and designed for use in case of two ruptures, one on each side of the abdominal cavity.

Figure 3 shows an enlarged fragmentary front elevation of the truss, and

Figure 4 shows an enlarged cross sectional view thereof.

Referring now more particularly to the drawings, wherein like numerals of reference designate similar parts in each of the figures the numeral 1 designates a flexible body, preferably of rectangular form, and composed of fabric material. This body has the opening 2 and carries a cup shaped support 3, formed of rubber, or other flexible material, and having a central opening 4,

which registers with the opening 2. A rigid annular plate 5 reinforces the bottom part of the support 3 and fitted through said plate and through the openings 2 and 4 there is a thimble 6 having the outer and inner annular flanges 7 and 8, the latter of which overlaps the plate 5, and the former of which overlaps the body portion 1, thus clamping the support 3 to the body 1, as well as forming a bearing through them. 60 There is a yieldable disc 9, preferably formed of rubber, and whose margin rests on the margin of the cup-like support 3, thus forming an annular space 10 between them and the disc 9, is formed with an integral projection 11, which works through the thimble 6 and whose outer end is slightly flared to anchor the disc 9 in place, but, said projection being yieldable, permitting the detachment of said disc 9. The central 65 part of the inner side of the disc 9 is slightly oval, as 12, and embedded in the material thereof there is a rigid anchor plate 13, preferably of metal, having a central tapped hole, aligned with the bearing 14, extending 70 axially through the disc 9. There is a retaining pad formed of a concavo-convex metallic disc 15, fixed to the outer end of the shank 16 and covered by the hood-like covering 18, preferably of aluminum, and of concavo-convex contour with the convex side 75 inwardly so as to rest against the body of the wearer. The shank 16 is threaded through the anchor plate 13 and the retaining pad is consequently adjustable. The retaining pad is made adjustable so as to 80 accommodate different conditions to be encountered.

The truss is retained on the body of the wearer with the retaining pad inwardly 85 against the body of the patient by means of a pair of body straps 19, 20, which are attached at their respective ends to the body 1 and which are provided with suitable releasable fasteners 22. A leg strap, as 23, 100 may be employed if desired and attached at its outer end to the lower body strap 20 and disposed around the corresponding leg and secured at its inner end to the end bearing rod 24, carried by the body 1, by means of the hook 25, carried by the free end of the leg strap 23. This forms a sliding engagement of the leg strap with the body of the truss allowing freedom of movement of the limb which the leg strap surrounds, with- 105 110

out binding or chafing. In the case of a double hernia and a double truss, as illustrated in Figure 2, two leg straps may be used, one disposed around each leg of the patient.

When the truss is applied to the body the pressure against the retaining pad will tend to cause the disc 9 to assume the position shown in dotted lines in Figure 4 and this position will vary as the pressure varies so that there will be a more or less constant movement of the pad 9 at its margins, as at 26, to exert a contracting pressure on the muscles surrounding the hernia opening, tending to reduce the size of said opening, as well as to massage said surrounding parts. The retaining pad, as well as the disc 9, are easily removable for cleansing purposes, or for the replacement of parts in case it becomes necessary to replace them.

What I claim is:

1. A truss including a flexible supporting body having a bearing, an annular support carried by said body and surrounding said bearing, a flexible disc whose margin rests on said support thus forming an annular enclosed chamber, a projection carried by said disc and working through said bearing and forming means to retain the disc in place

and a retaining pad carried by said disc 30 formed of rigid material and whose outer face is convex, said pad being adjustable relative to said disc.

2. A truss including a body, a yieldable disc spaced from said body, means interposed between the margin of the disc and the body and supporting the disc in spaced relation to said body, a retaining pad anchored to said disc and means for securing the truss to the body of a patient, said securing means 35 including a leg strap, one end of which is secured to the truss, a bearing rod carried by the truss body and an engaging means carried by the other end of the leg strap and adapted to engage and form a sliding bearing 40 on said rod.

3. A truss including a truss body, a bearing rod carried thereby and forming an anchor, a body strap secured to said body and adapted to surround the body of the wearer, 45 a leg strap attached at one end to the truss and a hook carried by the other end of said leg strap and adapted to slidably engage said rod.

In testimony whereof I have signed my 50 name to this specification.

AUGUST F. LUZZI.
